US00D852737S

(12) **United States Design Patent** (10) Patent No.: **US D852,737 S**
Andre et al. (45) Date of Patent: ** Jul. 2, 2019

(54) **BATTERY**(71) Applicant: **Apple Inc.**, Cupertino, CA (US)(72) Inventors: **Bartley K. Andre**, Palo Alto, CA (US); **Mikael Silvanto**, San Francisco, CA (US); **David P. Tarkington**, Sunnyvale, CA (US); **Joshua Funamura**, San Jose, CA (US); **Ari Parsons Miller**, San Francisco, CA (US)(73) Assignee: **Apple Inc.**, Cupertino, CA (US)(**) Term: **15 Years**(21) Appl. No.: **29/618,886**(22) Filed: **Sep. 25, 2017****Related U.S. Application Data**

(63) Continuation of application No. 29/519,710, filed on Mar. 6, 2015, now Pat. No. Des. 805,027.

OTHER PUBLICATIONS

App. of Bartley K. Andre with U.S. Appl. No. 29/435,191, filed Oct. 20, 2012, entitled "Electronic Device" (unpublished).

Primary Examiner — Michelle E. Wilson*Assistant Examiner* — Sanjeev Paul(74) *Attorney, Agent, or Firm* — Saidman DesignLaw Group, LLC(57) **CLAIM**

The ornamental design for a battery, as shown and described.

DESCRIPTION

FIG. 1 is a top perspective view of a battery showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines illustrate structure or features that form no part of the claimed design.
